ATTORNEY

UNITED STATES PATENT OFFICE.

JOHN DANIEL HENDERSON, OF NASHVILLE, TENNESSEE.

SAFETY-RAZOR.

1,008,410.

Specification of Letters Patent. Patented Nov. 14, 1911.

Application filed July 28, 1910. Serial No. 574,408.

To all whom it may concern:

Be it known that I, JOHN D. HENDERSON, a citizen of the United States, residing at Nashville, in the county of Davidson and State of Tennessee, have invented a new and useful Safety-Razor, of which the following is a specification.

The invention relates to improvements in safety razors.

10 The object of the present invention is to improve the construction of safety razors, and to provide a simple, practical and attractive single edged safety razor of comparatively inexpensive construction, adapted 15 to present the general appearance of an ordinary razor and foldable in a similar manner.

A further object of the invention is to provide a safety razor of this character, 20 equipped with a guard for protecting the face of the user against injury and adapted to be honed or stropped in the ordinary manner without taking it apart or affixing additional parts.

25 With these and other objects in view, the invention consists in the construction and novel combination of parts hereinafter fully described, illustrated in the accompanying drawing, and pointed out in the claims here- 30 to appended; it being understood that various changes in the form, proportion, size and minor details of construction, within the scope of the claims, may be resorted to without departing from the spirit or sacrificing any of the advantages of the invention.

In the drawing:—Figure 1 is a side elevation of a safety razor, constructed in accordance with this invention. Fig. 2 is a longitudinal sectional view of the same, the 40 blade being shown in elevation. Fig. 3 is a longitudinal sectional view on the line 3—3 of Fig. 2. Fig. 4 is an edge view of the holder. Fig. 5 is a plan view of the blank from which the holder is formed. Fig. 6 is 45 an end elevation. Fig. 7 is a transverse sectional view on the line 7—7 of Fig. 2. Fig. 8 is a similar view on the line 8—8 of Fig. 1. Fig. 9 is a transverse sectional view on the line 9—9 of Fig. 2.

50 Like numerals of reference designate corresponding parts in all the figures of the drawing.

In the embodiment of the invention illustrated in the accompanying drawing, the 55 safety razor comprises in its construction a

holder 1, pivoted by a rivet 2 between the sides 3 of an ordinary razor handle, the safety razor presenting the general appearance of an ordinary razor and being foldable within the handle in a similar manner. The 60 holder is stamped or otherwise formed from a blank 4 of suitable sheet metal such as German silver. The blank, which is oblong, is composed of a narrow portion, which is bent into tubular form, the side edges 5 being spaced apart to permit the introduction of a blade 6. The blank is also provided with a wider portion, which is bent longitudinally around the filling piece 7, forming a casing or housing 8 for the filling piece 7. 70 The filling piece and the casing form a shank, which present flat side faces to the inner faces of the sides 3 of the handle of the razor, and the filling piece 7 is extended beyond the casing 8 and shaped to form a grip 75 9 to enable the razor to be grasped and held in the same manner as an ordinary razor.

The blade 6, which consists of thin steel, is sharpened at one edge and is secured within a clamp, composed of two sides or jaws 80 10, provided at their inner rear edges with registering eyes 11, through which passes a pintle rod 12. The sides or jaws 10 present flat faces to the blade 6, which is retained in position between the sides or jaws 10 by 85 means of studs 13, projecting from the inner face of one of the sides or jaws of the clamp and engaging perforations 14 in the blade 6. Any number of perforations and studs may be employed, and the hinged portion of the clamp is of a diameter to fit 90 within the tubular holder, the side edges 5 fitting against and engaging the outer faces of the sides or jaws of the clamp and retaining them in engagement with the blade, 95 whereby the latter is firmly held in the razor.

The pintle rod is provided with reduced 100 projecting terminals forming pivots 15 for an oscillatory guard 16 of approximately U-shape, constructed of a single piece of suitable metal and composed of spaced end portions 17 and a longitudinal body portion, arranged at the cutting edge of the blade and having the usual wave or sigmoidal configuration. The ends 17 are provided at their 105 terminals with perforations for the projecting pivot portions 15, and the guard extends around the cutting edge and the side edges of the blade when the parts are assembled, as clearly shown in Fig. 2 of the drawing. 110

When the clamp, the blade and the guard are introduced at the holder, the inner end of the guard is located between spaced portions 18 of the sides of the casing 8 of the holder, the metal at the longitudinal edges 19 being cut away at the inner end of the casing, and the filling piece being terminated short of the tubular holder to permit the inner end of the guard to operate between the spaced portions 18 of the sides of the casing. The guard has a limited movement when its inner end is located between the spaced side portions 18, and the play is just sufficient, as illustrated in Fig. 6 of the drawing, to permit the guard to protect the face of the person using the razor. When, however, it is desired to strop or hone the razor, the guard, the blade and the clamp are moved outwardly in the holder by pressing on the inner end of the guard to carry the latter opposite recesses 20 in the side edges 5 of the tubular portion of the holder. The recesses 20, which are located just beyond the spaced side portions, permit an increased vibratory movement of the guard sufficient, as illustrated in Fig. 8 of the drawing, to expose the edge of the blade of the razor for stropping and honing.

By this construction the blade may be honed and stropped without removing it from the razor, and the latter may be held and operated similar to an ordinary razor, while stropping or honing. Also it is unnecessary to affix any parts to the razor to put it in condition for honing or sharpening, and ready access is afforded to the blade to permit the same to be removed and replaced by a new blade when necessary.

Having thus fully described my invention, what I claim as new and desire to secure by Letters Patent, is:—

1. A safety razor provided with a blade having a pivotally mounted guard arranged to oscillate across the cutting edge of the blade, said razor being provided with means for limiting the oscillatory movement of the guard and having means for also permitting an increased oscillatory movement of the guard to permit the blade to be honed and stropped without removal from the razor.

2. A safety razor including a detachable blade, a clamp engaging and carrying the blade, an oscillatory guard connected with and carried by the clamp, and a handle having a pivoted holder detachably receiving the clamp and adapted with the clamp to fold within the handle.

3. A safety razor including a detachable blade, a clamp engaging and carrying the blade, a handle having a pivoted holder detachably receiving the clamp and adapted with the clamp to fold within the handle, and an oscillatory guard connected with and carried by the clamp and engaged by the holder to limit its swing, said holder being

also provided with means for permitting an increased oscillatory movement of the guard to expose the blade for honing or stropping.

4. A safety razor including a blade, a clamp engaging the blade, a handle having a pivoted holder receiving the clamp and adapted with the clamp to fold within the handle, and an oscillatory guard connected with the clamp and engaged by the holder to limit its swing, said holder having spaced portions for limiting the swing of the guard and provided beyond the same with recesses for permitting an increased movement of the guard to expose the blade for stropping or honing.

5. A safety razor including a blade, a clamp engaging the blade, a handle having a pivoted holder receiving the clamp, and a pivotally mounted guard oscillating across the cutting edge of the blade, said holder having spaced means for limiting the oscillatory movement of the guard and provided beyond such spaced portions with recesses to permit an increased movement of the guard to expose the blade for stropping or honing the blade, the clamp and the guard being slidably in the holder to arrange the guard either at the spaced portions or the recesses.

6. A safety razor including a detachable blade, a clamp composed of spaced sides or jaws engaging and carrying the blade and provided with alined eyes, and a pintle rod passing through the eyes and forming a hinge connection between the sides or jaws, a guard also pivoted to the clamp by the pintle rod, and a handle having a holder receiving the clamp and provided with means for limiting the movement of the guard.

7. A safety razor including a blade, a clamp composed of spaced sides or jaws engaging the blade and provided with alined eyes, and a pintle rod passing through the eyes and forming a hinge connection between the sides or jaws, a guard also pivoted to the clamp by the pintle rod, and a holder receiving the clamp and provided with means for limiting the movement of the guard for shaving and having means for permitting an increased movement of the guard to expose the blade for stropping or honing.

8. A safety razor including a detachable blade, a clamp composed of sides or jaws engaging the blade and provided with eyes, and a pintle rod passing through the eyes and forming a hinge connection between the sides or jaws and provided with reduced terminals forming projecting pivots, an oscillatory guard mounted on the said pivots and connected with the clamp by the said pintle rod, and a handle having a holder receiving the clamp.

9. A safety razor including a handle, a holder consisting of a tubular portion provided at its inner end with opposite recesses, and a casing extending from the inner end

of the tubular portion, a filling piece secured within the casing and terminating short of the inner end thereof, a blade, a clamp engaging the blade and fitted in the holder, and an oscillatory guard engaged by the holder and having a portion normally operating within the inner end of the said casing and movable toward said recesses, whereby an increased movement of the guard is per-

mitted to expose the blade for stropping and honing.

In testimony, that I claim the foregoing as my own, I have hereto affixed my signature in the presence of two witnesses.

JOHN DANIEL HENDERSON.
